(57) **CLAIM**

The ornamental design for a lighted incense burner, as shown and described.

DESCRIPTION

FIG. 1 is a perspective view of the lighted incense burner showing my new design; and,

FIG. 2 is a side elevation view with a cross-section of the base member of the invention taken along line 2—2 in FIG. 1.

The broken line showing of the incense element in FIGS. 1 and 2 is for illustrative purposes only and forms no part of the claimed design.
